UNITED STATES PATENT OFFICE

123,230

DESIGN FOR A PORTABLE SAW

Edward M. Saliba, Lawrence, and Merton C.
Vincent, Lynn, Mass.

Application May 3, 1940, Serial No. 92,110

Term of patent 14 years

To all whom it may concern:

Be it known that we, Edward M. Saliba and Merton C. Vincent, both citizens of the United States, residing respectively at Lawrence and Lynn, both in the county of Essex and Commonwealth of Massachusetts, have invented a certain new, original, and ornamental Design for a Portable Saw, of which the following is a specification, reference being had to the accompanying drawings, forming a part thereof.

Fig. 1 is a side elevational view of a portable saw showing our new design;

Fig. 2 is a front elevational view thereof with the handle shown partly broken away for convenience of illustration; and

Fig. 3 is a top plan view thereof.

We claim:

The ornamental design for a portable saw substantially as shown.

EDWARD M. SALIBA.
MERTON C. VINCENT.
